Primary Examiner — Charles D Hanson(74) *Attorney, Agent, or Firm* — Stetina Brunda Garred and Brucker(57) **CLAIM**

The ornamental design for a wheeled walker, as shown and described.

DESCRIPTION

FIG. 1 is a front perspective view of the wheeled walker of the present invention showing our new design;
 FIG. 2 is a rear perspective view thereof;
 FIG. 3 is a left side view thereof;
 FIG. 4 is a front view thereof;
 FIG. 5 is a right side view thereof;
 FIG. 6 is a rear view thereof;
 FIG. 7 is a top view thereof;
 FIG. 8 is a bottom view thereof;
 FIG. 9 is a front perspective view with forearm rests in lowered position;
 FIG. 10 is a rear perspective view with forearm rests in lowered position;
 FIG. 11 is a front perspective view in a collapsed configuration; and,
 FIG. 12 is a rear perspective view in a collapsed configuration.
